United States Patent Office

Des. 184,587
Patented Mar. 10, 1959

184,587

PLATE OR SIMILAR ARTICLE

Gerald S. Stone, Scarsdale, N. Y., assignor to Johnson Bros. (Hanley) Limited, Stoke-on-Trent, England, a British company

Application March 31, 1958, Serial No. 50,255

Term of patent 14 years

(Cl. D44—15)

In the drawing a top plan view of a plate or similar article of conventional configuration illustrates my new design.

I claim:

The ornamental design for a plate or similar article, substantially as shown and described.
